UNITED STATES PATENT OFFICE.

JOHN T. BRADLEY, OF LITTLEFALLS, NEW YORK.

SHOEMAKER'S MEASURING DEVICE.

SPECIFICATION forming part of Letters Patent No. 723,236, dated March 24, 1903.

Application filed February 7, 1902. Serial No. 93,102. (No model.)

To all whom it may concern:

Be it known that I, JOHN T. BRADLEY, a citizen of the United States, and a resident of Littlefalls, in the county of Herkimer and State of New York, have invented certain new and useful Improvements in Shoemakers' Measuring Devices, of which the following is a specification.

This invention relates to shoe-dealers' measuring devices; and it consists of certain novel features of construction, which will be hereinafter fully described and finally embraced in the claim.

Heretofore devices of this kind consisted of simply a bar or measuring-stick with a slideable stop adapted to register the length of the foot, no provisions being made with such device to ascertain the width of the foot nor the size of the shoe corresponding to the measurement of the foot.

With my improved measuring device the various measurements required for fitting shoes are readily obtained.

The accompanying drawing is a perspective view of my improved foot-measuring device.

A represents the measuring bar or stick, which is made of wood or other suitable material and which is made to a sufficient width to form a support for the sole of the foot when placed thereon. On the face of this bar are arranged two columns of graduations B' and B² the column B' indicating the number of the foot and the column B² the number of the shoe. Secured to one end of the measuring-bar is a heel-piece C, against which the heel of the foot is placed when the measuring device is used, the other end of the measuring-bar being provided with a handle D.

E represents a flexible measuring-strap slidably mounted at a right angle to the longitudinal direction of the measuring-bar, said strap being adapted to inclose the foot and

disclose the circumferential measurement of the same.

F represents a retaining-rod for the strap, 45 said rod being preferably made of a piece of wire extending over the graduations and secured at each end to the central portion of the measuring-bar. This wire holds the measuring-strap to the bar without interfering with the slideable movement of the strap on the bar.

In using the device the foot to be measured is placed on the face of the measuring-bar with the heel against the heel-piece C, the 55 size of the foot being indicated in the column B' and the size of the shoe for such foot being indicated in the left column, the circumferential measurements of the foot being obtained by inclosing the foot in the measuring-strap E, which is graduated in inches.

Having thus described my invention, what I claim as new, and desire to secure by Letters Patent, is—

A shoemaker's measuring device, comprising a measuring-bar adapted to form a foot-support said bar being provided on its face with two columns of graduations, B', and B², the graduations B' indicating the number of the foot placed thereon the graduations B² indicating the number of the shoe adapted for such foot, a heel piece or support attached to one end of said measuring-bar, the other end of the bar being provided with a handle, a flexible measuring-strap slidably mounted at 75 a right angle to the longitudinal direction of said bar, a retaining-rod for said strap extending over the said graduations from one end to the other and secured to the said bar, substantially as described.

JOHN T. BRADLEY.
